UNITED STATES PATENT OFFICE.

THOMAS LEE COLLINS, OF SARASOTA, FLORIDA.

DITCHING MACHINE.

Application filed September 29, 1925. Serial No. 59,392.

To all whom it may concern:

Be it known that I, THOMAS L. COLLINS, a citizen of the United States, residing at Sarasota, in the county of Sarasota and State 5 of Florida, have invented certain new and useful Improvements in Ditching Machines, of which the following is a specification.

This invention relates to excavators and more particularly to ditching machines.

10 An object of the invention is the provision of a ditching machine having improved means for conveying the earth dug from the machine.

A further object is to provide an apparatus 15 consisting of a rotary drum having knives arranged on its periphery and adapted to cut into the earth, the cut earth being delivered to the interior of the drum which is provided with agitators for reducing 20 clumps to a finer material more readily adapted to be passed through a conveyer.

In the accompanying drawings I have shown one embodiment of the invention. In this showing,

25 Figure 1 is a plan view,

Figure 2 is a side elevation,

Figure 3 is a vertical sectional view on line 3—3 of Figure 1,

30 Figure 4 is a vertical sectional view on line 4—4 of Figure 2,

Figure 5 is a vertical sectional view on line 5—5 of Figure 1,

Figure 6 is a side elevation of the cutting drum viewed from the opposite side from 35 Figure 2,

Figure 7 is a vertical sectional view through the drum taken on line 7—7 of Figure 5,

40 Figure 8 is an enlarged sectional view of a portion of the drum taken in substantially the same plane as Figure 5, and,

Figure 9 is a detail view of a portion of the main shaft.

45 Referring to the drawings, the apparatus comprises an upper frame consisting of side members 1 which are connected at their ends by cross members 2. An auxiliary longitudinal member 3 is arranged between the side members and a pair of inner transverse members 4 are provided which extend beyond the side members and are connected by a longitudinally extending member 5. The machine is further provided with a lower frame 6 connected to the upper frame by vertical members 7 and inclined members 8. In operation the lower frame is spaced

slightly above the ground level as shown in Figure 2 of the drawings and the apparatus is drawn or otherwise conveyed over the land by means of a tractor or the like.

An engine 9 or other source of power is mounted on the upper frame and the main shaft of the engine is connected to a transmission 10. The transmission shaft extends into a gear box 11 provided with suitable gearing (not shown) adapted to drive a main shaft 12. The cutter consists of a drum 13 formed of spaced side walls as shown in Figure 5 of the drawings and this cutter is mounted on the main shaft 12 to 70 revolve therewith. As shown the shaft is supported in suitable bearings 14 carried by the lower frame. Between the side walls of the cutter I provide a plurality of curved plates 15 which project beyond the edges 75 of the plates and are provided with knife edges 16. The main shaft is provided with a suitable clutch 17 controlled by a lever 18 by means of which the drum may be connected to the source of power. Surrounding 80 the main shaft I provide a conveyer shell 19 having a ribbon conveyer 20 arranged therein and this conveyer shell extends within the drum and is provided with an opening 21 through which the dirt within the drum passes into the conveyer. On one side of the conveyer I provide a tooth 22 which is adapted to engage the earth slightly in advance of the cutters 16 forming a clean cut side wall. On the frame adjacent the 85 drum I provide an arcuate plate 23. Within the drum I provide a plurality of rolls 24 arranged between the pairs of plates 15 and these rolls are provided with projecting teeth or prongs 25 and serve as agitators. 90 As shown, the rolls are mounted on suitable shafts 26 which are journaled in the side walls of the frame as at 27 and provided with suitable ball bearings 28. On the side of the drum adjacent the plate 23 the shafts 26 are provided with friction rollers 29 which are adapted to contact with the curved plate 23 to revolve the agitators.

95 The conveyer shell 19 communicates with a longitudinally extending inclined conveyer 105 consisting of a substantially trough shaped member formed of a bottom 30 and side walls 31. At one end of this conveyer there is provided a shaft 32 having a hollow drum 33 mounted thereon. This drum is provided with an opening 34 in one of its end walls through which the material passes from

the conveyer shell 19 and is further provided with spaced openings 35 in its periphery through which the material passes into the conveyer casing. At the opposite end 5 of the trough there is provided a conveyer drive shaft 36 which extends across the rear of the machine (see Figure 1) and is provided with a bevel gear 37 on its opposite end mounted in a suitable gear box 38. As 10 shown, the shaft is supported in a bearing 39 adjacent its end which bearing is carried by the frame of the machine. The conveyer drive shaft is driven from the main shaft by means of a longitudinally extending main 15 shaft 40 which is mounted in suitable bearings 41 carried by the frame and is provided with a bevel gear 42 within the gear box 38 meshing with the bevel gear 37. The opposite end of the shaft 40 is provided 20 with a bevel gear 43 meshing with the bevel gear 44 on the main shaft.

As shown (see Figure 3) a drum 45 is mounted on the conveyer shaft within the conveyer casing. An endless member consisting of side sections 46 connected by transverse plates 47 passes over the drums 33 and 45 and conveys the material along the bottom of the conveyer 30 to the rear of the machine whence it is dumped at one side 30 of the ditch.

The operation of the device will be apparent from the foregoing description. The machine is drawn over the surface and with the lower frame 6 substantially on the level 35 of the surface the drum 13 projects below the surface. When the clutch 17 is connected to rotate the drum the knife edges 16 dig into the earth to form a ditch of substantially the same width as the drum as indicated in Figure 2 of the drawings. As 40 stated, the knife 22 arranged on the side gives a clean cut bank or side wall and also forms a clearance for the friction rollers 29. These rollers are revolved during that 45 portion of the revolution when they are in engagement with the arcuate plate 23 and the agitating rolls in the drum break up the material cut by the knives. The material cut is retained in the spaces between 50 the curved plates 15 until it reaches the upper portion of the drum whence it is delivered by gravity into the conveyer shell 19 and thence carried to the main conveyer at the side of the machine. The material 55 is then carried upwardly along the bottom

of the main conveyer by the transverse members 47 and dumped.

It is to be understood that the form of my invention herewith shown and described is to be taken as a preferred example of the same, and that various changes in the shape, size, and arrangement of parts may be resorted to without departing from the spirit of the invention or the scope of the subjoined claims.

65

I claim:

1. In a device of the character described, a frame, a drum rotatably mounted on said frame, said drum comprising spaced side walls and plates arranged between said walls and extending beyond the peripheral edges of said walls, the outer edges of said plates being provided with knife edges, a cutting element carried by one of said walls on the exterior and projecting beyond the edge of 75 the wall, a conveyer arranged beside said drum, and a second conveyer extending axially of said drum and adapted to deliver material from said drum to said first conveyer.

2. In a device of the character described, 80 a frame, a drum rotatably mounted on said frame, said drum comprising spaced side walls and plates arranged between said walls and extending beyond the peripheral edges of said walls, the outer edges of said plates 85 being provided with knife edges, an arcuate plate carried by said frame and disposed beside said drum, a plurality of shafts journaled in the walls of said drum, friction rollers carried by said shafts exteriorly of 90 said drum and adapted to engage said arcuate plate to rotate said shafts, and agitators carried by said shafts.

3. A device constructed in accordance with 95 claim 2 wherein said agitators consist of rollers having a plurality of projecting prongs arranged thereon.

4. In a device of the character described, 100 a frame, a drum rotatably mounted on said frame, said drum comprising spaced side walls and plates arranged between said side walls and extending beyond the peripheral edges of said walls, the outer edges of said plates being provided with knife edges, 105 agitators arranged between said plates, a conveyer arranged beside said drum, and means for delivering material from said drum to said conveyer.

In testimony whereof I affix my signature.

THOMAS LEE COLLINS.
